UNITED STATES PATENT OFFICE.

HUGO NEUMAN, OF DETROIT, MICHIGAN, ASSIGNOR TO DIAMOND MANUFACTURING COMPANY, OF DETROIT, MICHIGAN, A CORPORATION OF MICHIGAN.

METAL-SHAPING MACHINE.

1,091,469.

Specification of Letters Patent. Patented Mar. 24, 1914.

Application filed January 27, 1912. Serial No. 673,922.

To all whom it may concern:

Be it known that I, HUGO NEUMAN, a citizen of the United States of America, residing at Detroit, in the county of Wayne and 5 State of Michigan, have invented certain new and useful Improvements in Metal-Shaping Machines, of which the following is a specification, reference being had thereto in the accompanying drawings.

10 My invention relates to metal shaping machines, and has among the objects thereof to provide a machine of simple construction which will progressively shape a strip into the desired form as it is passed through the 15 machine and which will permit the strip to be continuously and rapidly fed to the machine; to provide means for easily and accurately relatively adjusting the coöperating forming members; and to feed the 20 strip through the machine so as to avoid drawing thereof.

Other objects of my invention will more fully hereinafter appear.

The invention resides in the peculiar construction, arrangement and combination of parts as herein described and particularly pointed out in the claims.

In the drawings,—Figure 1 represents a side elevation of a machine embodying my 30 invention; Fig. 2 is a similar view, looking in the opposite direction; Fig. 3 is a top plan view with the guide rollers removed; Fig. 4 is a section on the line $x-x$ of Fig. 3; Fig. 5 is a perspective view of a channel 35 member formed by the machine; Figs. 6, 7 and 8 are side elevations of the several pairs of forming rolls; Figs. 9 to 12 inclusive illustrate different stages of the metal strip during forming; Figs. 13 to 17 inclusive are elevations of the several dies; Fig. 18 is a perspective view of the mandrel; Fig. 19 is a section on the line $y-y$ of Fig. 3; and Fig. 20 is a detail view, showing one of the bolts.

45 A represents the bed of the machine, which bed is formed of a single casting provided with a plurality of spaced transverse bores $a a' a''$ extending therethrough, and with a corresponding number of recesses $b b' b''$ arranged directly above the bores. Journaled in the former are shafts $B B' B''$, and rotatively mounted in the recesses are shafts $C C' C''$. The ends of these several pairs of shafts project without their bearings, and 50 at one side of the bed the shafts $B B' B''$

have fixed thereto forming rolls $D D' D''$, which coöperate with complementary rolls $E E' E''$ upon the shafts $C C' C''$. At the opposite side of the bed the pairs of shafts are provided with intermeshing gears $c c' c''$, 60 and the shafts $B B' B''$ also have secured thereto sprockets $d d' d''$ which are driven through the medium of a chain e from a drive sprocket f . The latter is preferably rotated through the medium of a pulley f' 65 and a belt f'' leading to a suitable source of power. By this arrangement, when the sprocket f is set in operation, all of the forming rolls are positively driven. To prevent the chain from leaving the sprockets, 70 guide and tension rolls $S S' S''$ are provided, which are suitably journaled on stub shafts S^3 .

The stub shafts for the rolls $S S'$ are secured to the bed, while the stub shaft for 75 the roll S'' is carried by an arm S^4 , which is slotted at its lower end at S^5 to adjustably engage a clamping screw S^6 upon the bed. Thus, by adjusting the arm the desired tension may be placed upon the chain. 80

Each of the shafts $C C' C''$ is journaled in a bore F in and eccentric to a tubular sleeve G rotatably mounted in the bottom of the recess. This sleeve is held to the recess bottom by a block H provided on the top 85 thereof with bores I for receiving springs g which yieldably hold the block in engagement with the sleeve. Preferably two of these springs are employed, one adjacent each end of the block, and all of the springs 90 are held under the desired compression by a plate J secured to the top of the bed as by bolts h , the plate having counterbores h' for receiving the upper ends of the springs. Each of the springs is adjusted by means of 95 a set-screw h^2 engaging a plate i^2 forming an abutment for the top of the spring. Thus, the tension upon the several sets of rolls may be independently adjusted. At one side of the bed each sleeve is provided 100 with a handle i for rotating the same in the recess, so as to lower or raise the shaft, thereby moving the forming rolls upon the shaft toward or from its coöperating rolls. This handle is held in its adjusted position 105 by a pair of abutments such as bolts $K L$ positioned upon opposite sides of the handle, each bolt having a nut j slidably engaging an undercut recess h in the side edge of the plate J , and being provided with a sleeve 110

7 interposed between the head of the bolt and the side of the plate. By tightening the bolt, the sleeve will be clamped against the end of the plate, while the abutment 5 may be moved longitudinally of the slot to permit the adjustment of the handle by slightly unscrewing the bolt.

The machine illustrated in the drawings is especially designed for making a channel-shaped strip M of the form shown in Fig. 5, which is employed as a resilient bearing for the edge of a glass panel. This strip has the side edges o thereof rebent to provide inwardly extending portions o' spaced from 10 the sides, while the latter and the bottom p of the channel are slightly grooved, as indicated by the reference-letters q r. The strip is formed from a flat ribbon of metal continuously fed to the machine from a 15 supply reel not shown.

In operation, the flat ribbon is fed from the reel over a guide roll O' to the rolls D E, from which it passes to a die P, then through the rolls D' E' D² E² to a die Q, 20 the strip as it leaves the latter having the finished form. Taking up in detail the several steps of progressively shaping the strip—the roll E has formed in the face thereof a groove a³ and projections b³ and 25 c³, while the roll D has a complementary projection d³ and grooves e³ and f³ positioned in operative relation to the grooves and projections. The portions a³ d³ serve to 30 shape the groove q in the part of the strip which forms the bottom of the channeled article, while the portions b³ e³ and c³ f³ slightly bend the sides, the strip as it leaves 35 these rolls having the form shown by Fig. 9. The die P at the forward end has substantially the same cross-section as that of the strip when it leaves the rolls D E, but the 40 longitudinal section of this die gradually tapers to the form illustrated in Fig. 13, serving to roll the edges of the strip inward, giving the latter the contour of Fig. 45 10. In passing through the rolls D' E' the edges are rolled slightly further, the members D' E' having coöperating grooves g³ h³ adjacent the sides of their faces for effecting this operation. At the center, however, 50 the coöperating surfaces are the same as the central portion of the rolls D E. The strip leaves the rolls D' E' in the form shown by Fig. 11, and as it passes through the forming rolls D² E² is partially channeled. The 55 face of the roll D² is grooved or channeled at i³, the bottom j³ of the groove having the same shape as the projection d³ on the roll D, that is the configuration of the bottom p' 60 of the finished product, while the sides of the groove are diverged. k³ is a projection upon the roll E², having a face l³ of a contour complementary to the portion j³ of the member D², but the sides of this projection 65 are straight and spaced a sufficient distance

from the diverging sides to permit the beaded ends of the strip to pass there-through. Passing from this last set of forming rolls the strip as it is fed to the die. Q has the configuration shown by Fig. 12. 70 This die comprises a plurality of spaced forming members Q' Q² Q³ Q⁴, through which passes a mandrel Q⁵. The forming apertures of these members gradually decrease in size from the member Q' to Q⁴ 75 (see Figs. 14 to 17 inclusive), and the apertured portion of each member tapers in longitudinal section from the entrance to the exit side thereof, as will be seen upon reference to Fig. 19. The mandrel Q⁵ is 80 slightly tapered longitudinally from its forward end, while the bottom and sides are slightly concaved to fit the bottom and sides of the channel strip. As it passes through the die Q, the form of the member is progressively changed from that shown in Fig. 12 to the finished strip. 85

In the construction of resilient bearing illustrated in Fig. 6, it is desirable to temper the base, but to avoid tempering of the sides. This result is accomplished in the following manner: The several pairs of shafts are driven at the same speed, but the circumference of the roll D is greater than that of the roll E, producing a difference in speed between the coacting surfaces. The portions a³ d³ of the rolls are yieldably held in contact with the strip, but the remaining portions of the forming surfaces of the rolls D E are slightly spaced. Therefore, as the strip is fed through these rolls the difference in speed of the portions a³ d³ will tend to slightly lengthen the middle of the strip, which is substantially taken care of by a slight lateral flowing of the metal. Any distortion of the strip is more or less remedied by the die P, but as the strip passes into engagement with the rolls D' E' the strip is straightened. The pressure of the roll E' is greater than that of the roll E, and also the central portions of the peripheries of the second set of rolls are the only parts of the forming surfaces that are in engagement. The variation between the circumferences of the second pair of rolls is the same as that of the first, and as the strip passes through the members D' E' a further tempering of the center thereof will be effected. The difference in circumference between the working faces of the rolls D² E² is considerably greater than the variation between the circumferences of the first two sets of rolls; likewise, the tension placed upon the roll E² through the medium of its spring g is much greater than that of the roll E'. In passing through the rolls D² E² the operation of tempering the base is completed, and this is effected simultaneously with the channeling of the strip. 110 115 120 125

From the foregoing description it will be 130

understood that the central portion of the strip is progressively tempered and that the sides are partially beaded and shaped before the strip is bent into channel form.

5 In metal bending machines where the article is of comparatively small cross-section, a slight variation in the thickness of the metal is quite frequently highly objectionable. The fact that the thickness of 10 the metal strip differs slightly is of little importance in the initial steps of shaping the strip, but as the opening in the finishing die is more or less restricted a very slight unevenness in the metal passing there-through tends to give the latter an uneven 15 or varying cross-section and also produces a drawing of the sides. To overcome this objection, I have arranged the mandrel within the members Q' Q^2 Q^3 Q^4 , so that it 20 will be free to move, within certain limits, in relation to the forming apertures thereof. As shown, the mandrel is provided with a vertical projection n^3 which is arranged within a slot o^3 in the member Q' and has 25 the forward end thereof positioned to abut against the member Q^2 , the forward movement of the mandrel being thereby limited. The portion of the mandrel which passes through the forming apertures is of a size 30 sufficiently smaller than the latter to adjust laterally or vertically, so as to compensate for any uneven thickness in the strip.

The members of the die Q are supported upon a bracket R which has recesses R' 35 within which the lower edges of these members are seated, the latter being secured within their seats by spacing plates S' that are clamped thereto by screws S^2 .

What I claim as my invention is:

40 1. In a metal shaping machine, the combination with a bed, of a pair of shafts carried thereby, coöperating forming rolls fixed on said shafts, means for driving said shafts to produce a difference in speed between the 45 coöperating faces of the rolls, and means for yieldably pressing one of the shafts toward the other.

2. In a metal shaping machine, the combination with a bed, of a pair of shafts carried thereby, coöperating forming rolls fixed on said shafts, means for driving said shafts to produce a difference in speed between the coöperating faces of the rolls, and means for yieldably pressing one of the shafts toward the other, the coöperating faces of the forming rolls having a portion of their work engaging faces spaced a greater distance than the remaining portions thereof.

3. In a machine for shaping flat metallic strips the combination with a bed, of a pair of shafts carried thereby, coöperating forming rolls fixed on said shafts and means for driving said shafts to produce a difference in speed between the coöperating faces of 65 the rolls, said rolls having a portion only of

their work engaging faces adapted to exert a metal spreading pressure upon the strip.

4. In a machine for shaping flat metallic strips, the combination with a bed, of a plurality of pairs of forming rolls mounted thereupon, means for driving the members of each pair of rolls to produce a difference in speed between the coöperating faces thereof, the rolls of each pair having a portion only of their work engaging faces adapted 70 to exert a metal spreading pressure upon a portion of the strip.

5. In a machine for shaping flat metallic strips, the combination with a bed, a plurality of pairs of forming rolls mounted 80 thereupon for progressively shaping a portion of the cross-section of the strip and for progressively tempering another portion of the cross-section of the strip during the shaping.

6. In a machine for shaping flat metallic strips, the combination with a bed, of a plurality of pairs of forming rolls mounted thereupon for progressively shaping a portion of the cross-section of the strip and for 90 progressively tempering another portion of the cross-section of the strip during the shaping, and a die beyond the forming rolls for shaping the strip without drawing.

7. In a machine for forming channel 95 strips from flat metallic ribbon, the combination with a bed, of a plurality of pairs of rolls mounted thereupon for partially shaping the edges of the ribbons and simultaneously partially tempering the center of 100 the ribbon, and a pair of channel rolls adapted to temper the center of the strip simultaneously with the channeling.

8. In a machine for forming channel strips from flat metallic ribbons, the combination with a bed, of a plurality of pairs of forming rolls mounted thereupon for partially shaping the edges of the ribbon and simultaneously partially tempering the ribbon center, a pair of channeling rolls adapted 105 to temper the center of the strip simultaneously with the channeling, and a finishing die arranged beyond the channeling rolls.

9. In a machine for shaping flat metallic 115 strips, the combination with a bed, of a plurality of pairs of forming rolls mounted thereon for progressively shaping the strip, a finishing die beyond the rolls, comprising a plurality of spaced members provided with 120 openings for progressively shaping the strip, and a mandrel extending through said openings and freely movable in relation to said members within certain limits.

10. The combination with a bed, of a plurality of pairs of shafts, one member of each pair being journaled in a fixed bearing, an adjustable bearing within which the other member is journaled, intermeshing gears on each pair of shafts, a drive connection be- 125 130

1. The combination with a bed, of a bearing in said bed, a shaft journaled in said bearing, and coöperating forming rolls on said shafts.
2. The combination with a bed, of a bearing in said bed, a shaft journaled in said bearing, an adjustable eccentric sleeve carried by the bed, a complementary shaft journaled in said sleeve, and coöperating forming rolls mounted on said shafts and arranged at one side of the bed.
3. The combination with a bed, of a bearing in said bed, a shaft journaled in said bearing, a spring pressed adjustable eccentric mounted on said bed, a complementary shaft journaled in said eccentric, and coöperating forming rolls mounted on said shafts.
4. The combination with a bed, of a bearing in said bed, a shaft journaled in said bearing, an adjustable eccentric sleeve carried by the bed, a complementary shaft journaled in said sleeve, coöperating forming rolls mounted on said shafts, a handle without the bed for adjusting said sleeve movable about the axis of the latter, and means on the bed for retaining the handle in its adjusted position.
5. The combination with a bed having a bore formed therein and provided with a recess, a shaft journaled in said bore, an eccentric sleeve mounted in said recess, a spring pressed member for yieldably holding said eccentric sleeve in place, means for varying the tension placed upon said member, a shaft journaled in said sleeve, and coöperating forming rolls mounted on said shafts.
6. The combination with a bed having a bore formed therein and provided with a recess, a shaft journaled in said bore, an eccentric sleeve mounted in said recess, a spring pressed member for yieldably holding said eccentric sleeve in place, means for varying the tension placed upon said member, a shaft journaled in said sleeve, coöperating forming rolls mounted on said shafts, and a handle without the bed for adjusting said sleeve.
7. The combination with a bed, of a bearing in said bed, a shaft journaled in said bearing and having portions extending upon opposite sides of the bed, an adjustable eccentric sleeve carried by the bed, a complementary shaft journaled in said sleeve and also having portions projecting upon opposite sides of the bed, coöperating forming rolls mounted on the projections of said shafts at one side of the bed, and coöperating gears fixed to the projections of the shafts upon the opposite side of the bed.
8. The combination with a bed, of a plurality of bearings in said bed, shafts journaled in said bearings, a plurality of spring-pressed adjustable eccentrics mounted on the bed, complementary shafts journaled in said eccentric, coöperating forming rolls mounted on said shafts, and means for independently adjusting the springs of the eccentrics.
9. The combination with a bed having a plurality of bores therein and provided with a corresponding number of recesses, shafts journaled in said bores, eccentric sleeves mounted in said recesses, a spring-pressed member for each sleeve acting to yieldably hold the same in place, a cap for the bed extending across said recesses, means for independently varying the tension placed upon said spring-pressed member, shafts journaled in the sleeves, and coöperating forming rolls mounted on said shafts.
10. In a metal shaping machine, the combination with a bed, of a plurality of pairs of shafts carried thereby, coöperating forming rolls fixed on each pair of shafts having faces for shaping the metal, means for yieldably pressing one of the shafts of each pair toward the other, and a common drive train for simultaneously and positively driving all of said shafts.

In testimony whereof I affix my signature in presence of two witnesses.

HUGO NEUMAN.
